UNITED STATES PATENT OFFICE

154,530

DESIGN FOR A GRINDER OR THE LIKE

William B. Boice, Toledo, Ohio, assignor to Boice-Crane Company, Toledo, Ohio, a corporation of Ohio

Application December 6, 1948, Serial No. 150,013

Term of patent 14 years

(Cl. D37—1)

To all whom it may concern:

Be it known that I, William B. Boice, a citizen of the United States of America, residing at Toledo, Lucas county, Ohio, have invented new, original, and ornamental Design for a Grinder or the like, of which the following is a specification, reference being had to the accompanying drawings.

Fig. 1 is a perspective view of a grinder or the like, showing my new design; and

Fig. 2 is a side elevational view of the side opposite that shown in Fig. 1.

The end not shown is substantially plain.

I claim:

The ornamental design for a grinder or the like, as shown and described.

WILLIAM B. BOICE.
